CLAIM

The ornamental design for a charging station for electric vehicles, as shown and described.

DESCRIPTION

1.1 is a perspective view of the front, top, and right side of a charging station for electric vehicles;

1.2 is a front elevation view of the charging station;

1.3 is a rear elevation view of the charging station;

1.4 is a right side elevation view of the charging station; and

1.5 is a bottom plan view of the charging station.

The broken lines and portions within the broken lines illustrate portions of the charging station that form no part of the claimed design.
